UNITED STATES PATENT OFFICE.

FRANK R. NICE, OF LANSING, MICHIGAN.

RUBBER-DAM HOLDER AND CUTTER.

SPECIFICATION forming part of Letters Patent No. 760,800, dated May 24, 1904.

Application filed September 12, 1903. Serial No. 173,011. (No model.)

To all whom it may concern:

Be it known that I, FRANK R. NICE, a citizen of the United States, residing at Lansing, in the county of Ingham and State of Michigan, have invented new and useful Improvements in Rubber-Dam Holders and Cutters, of which the following is a specification.

This invention relates to a rubber-dam holder and cutter; and the primary object of the same is to provide a simple and effective device for holding a roll of rubber dam and a knife attachment whereby the rubber can be cut any length desired in a straight and regular manner.

15 The invention consists, primarily, of a base with a cylinder supported at one end thereof, one end of the cylinder being removable for the ready insertion of a roll of rubber dam and said cylinder also having a slot therein whereby the dam may be drawn therefrom and a holding device with which a rotatable cutter operates to separate the dam in lengths required.

25 While the improved device is particularly adapted for use in separating or cutting rubber dam into suitable lengths, it will be understood that it may be employed for other purposes—as, for instance, in separating paper or other material.

30 In the accompanying drawings, Figure 1 is a perspective view of a rubber-dam holder and cutter embodying the features of the invention. Fig. 2 is a transverse vertical section taken through the plane of the clamp or 35 the retaining means for the dam or other material adapted to be cut by the improved device. Fig. 3 is a longitudinal vertical section of the improved device. Fig. 4 is an end elevation of the cutter, showing the parts with 40 which it co-operates in dotted lines.

Similar numerals of reference are employed to indicate corresponding parts in the several views.

The numeral 1 designates a bed or base of 45 suitable material having thereon a resisting-sheathing 2 of some suitable metal, preferably zinc. At one end of the base are a pair of uprights 3, supporting a cylinder 4, having one end removable and a slot or feed- 50 opening 5 in the lower portion thereof. The

zinc sheathing or covering 2 is of limited extent respecting its width and is located in advance of the cylinder 4, said sheathing or covering being countersunk in the bed 1, so that the upper surface thereof will be flush 55 with the similar surface of the bed. This sheathing has a pressure member or clamp 6 hinged to one end thereof and provided with an upper guide 7, which is partially cylindrical and also includes a vertical web 8, which projects downwardly into the main body 60 of the clamp. Freely movable on the guide 7 is a head 9, having a circular aperture 10 extending therethrough to engage the cylindrical portion of the guide and a slot 11 opening 65 out through the bottom thereof to permit the lower part of the head to embrace the web 8, so as to keep the head as an entirety in close engagement with the guide to prevent irregular or wobbling movement thereof. The head 70 9 has a cutting-disk 12 rotatably held on the side thereof opposite the side contiguous to the cylinder 4, the parts being so proportioned and arranged that the cutting-disk 12 will firmly bear against the edge of the clamp or 75 holding device 6 opposed to the edge of such device nearest the cylinder. The disk 12 is movable in contact with the metallic sheathing or covering 2 and is of harder metal than the latter, so that the cutting edge thereof 80 will not be injured by contact with the sheathing. As a matter of convenience in raising and lowering the clamp projections 13 are provided at opposite ends of the latter and the head 9 is so shaped, as at 14, that it may be 85 conveniently engaged by the fingers of the hand of the operator.

In the use of the improved dam holder and cutter the rubber dam is pulled outwardly from the cylinder 4 over the upper surface of 90 the bed 1 after the clamp 6 has been elevated or thrown over to one side. The length of the dam desired having been determined, the clamp 6 is thrown downward in a horizontal position and held with one hand in close contact with the dam, while the opposite hand of the operator is used in moving the head 9 and its cutting-disk over the dam and severing the length of the latter desired.

95 As before indicated, the improved device 100

may be used for other means or for cutting other materials, but is especially adapted for cutting rubber dams into suitable lengths. In some instances the cutter may be employed 5 for forming an opening in an intermediate portion of the dam when required for certain operations, and for different kinds of work it is proposed to modify the dimensions and proportions and minor details of construction 10 without departing from the spirit of the invention.

Having thus fully described the invention, what is claimed as new is—

1. In a device of the class set forth, the 15 combination of a base, a tubular holding means at one end of the base, a clamping device hinged at one end on the base in advance of the holding means, and a slidable head carried by the clamping device and having a rotating cutter thereon.
2. In a device of the class set forth, the 20 combination of a base, a tubular holding means at one end of the base, a clamping device hinged to the base and adapted to be disposed transversely over the latter, the said clamping 25 device having a metal guide, a head movable on the guide, and a rotatable disk cutter carried by the head and operative close to one edge of the clamping device.
3. In a device of the class set forth, the 30

combination of a base, a tubular holding means at one end of the base, a clamp movably attached to the base and adapted to be disposed transversely over the latter, a metal covering on which the clamping device is adapted to 35 rest, and a slidable cutter carried by the clamping device and normally having contact with the metal covering.

4. In a device of the class set forth, the 40 combination of a base, a tubular holding means located at one end of the base, a clamping device movably attached to the base, and a slideable cutter carried by the clamping device and adapted to contact with a portion of the base.

5. In a device of the class set forth, the 45 combination of a base, a tubular holding means located at one end of the base, a clamping device movably attached to the base, and a rotatable cutter carried by the clamping device 50 and adapted to contact with a portion of the base, said cutter being movable transversely over the base.

In testimony whereof I affix my signature in presence of two witnesses.

FRANK R. NICE.
